UNITED STATES PATENT OFFICE

HERBERT R. SPENCER, OF ERIE, PENNSYLVANIA, ASSIGNOR TO PORCELAIN TILE CORPORATION, A CORPORATION OF DELAWARE

METAL TILE WALL STRUCTURE

Application filed October 3, 1929. Serial No. 397,013.

The present invention is designed to improve metal tile. These tiles are formed of sheet metal and preferably coated with vitreous enamel giving them the appearance of the ordinary tile. It is desirable in the formation of such tile to provide a simple means of securing the tile to a backing so as to form a tile wall and in order to improve the appearance by dividing the tile surface into sections as with ordinary tile it is desirable to separate the tile into units with a cement filler and where such filler is used it is necessary to lock the filler in place. This can preferably be accomplished by spacing the tile from the backing. In arranging for such spacing a preferred means is to utilize the attaching lugs for accomplishing this spacing. The provision of this spacing not only forms the means for locking the cement through the extension of the cement under the edges of the tile, but the cement forms a very secure seat for the tile, thus preventing any yielding of the tile under pressure which would tend to loosen the cement and give an impression of lack of solidity of the wall. The invention contemplates also the formation not only of single tile units with securing means but tile plates in which a plurality of units are formed and united. Preferably the units of these plates are separated so as to provide cement spaces corresponding to the cement between the plates. This arrangement adds to the convenience and ease with which a wall may be formed. Features and details of the invention will appear from the specification and claims.

A preferred embodiment of the invention is illustrated in the accompanying drawing as follows:

Fig. 1 shows a perspective view of a tile plate.

Fig. 2 a perspective view of a wall structure with the tile in place.

Fig. 3 a section on the line 3—3 in Fig. 1.

Fig. 4 an elevation of the tile plate.

Fig. 5 an individual tile unit.

Fig. 6 a section on the line 6—6 in Fig. 2.

Fig. 7 a section on the line 7—7 in Fig. 2.

A marks a wall backing. This may be of any form suitable for receiving nails, or

similar securing means and preferably is a closed backing at least at the points of separation. The tile plate is made up of a number of tile units 1. These tile units are flanged around their edges at 2. Securing projections 3 and 4 extend from the edges of the plate. There are a plurality of these at the outer edge of each unit and they are off-set relatively to a central line similarly on all edges so that the projections on each edge 60 of each plate may underlie the adjacent plate. The projections 3 and 4 are beneath the plane of the plate and the plate is preferably spaced from the back wall with such projections in engagement with the wall and this space 65 affords a means by which the projections may be readily slipped under an adjacent plate and also is of very material advantage as hereinafter described. The units 1 have the cut-out spaces 5 between them and are 70 connected at intervals at their adjoining corners by straps 6 and nearer the outer edges of the plate by straps 7. Cement 8 is forced into the spaces 5 and into spaces 5a between the adjacent plates after the tile plates are 75 secured to the wall backing. This cement 8 under pressure as it is forced into the space flows into spaces 9 under the edges of the tile. Extensions 8a of cement form locks, or keys for anchoring the cement securely in 80 the spaces and also form a close fitting seat for the tile so as to prevent any looseness of the tile, the cement forcing the tile outwardly to take up any looseness. To this end the bridges 6 and 7 are comparatively narrow 85 so that there may be no great length of the cement which is not supported by the extending lock.

In Fig. 5 a single unit 10 is shown. With the exception of the projections 11 and 12 90 for the straps 6 and 7 the unit 10 is similar to the unit 1. It is laid up in the same manner as the tile plates, the spacing between the several tiles being filled with cement and having the locking extensions as with the 95 tile plate. This unit is useful in filling out spaces of wall where less than an entire tile plate is required and, if desired, an entire wall may be laid up with the individual units. As before stated, the tile is preferably coated 100

with a vitreous enamel which may be made to correspond in color and surface texture with the ordinary vitreous tile.

What I claim as new is:—

- 5 1. A metal tile wall comprising a supporting wall backing; metal tile plates, each having a plurality of tile units spaced one from another, the plates being cut through between the units and having joining straps 10 at intervals, said plates having securing projections along their edges, said joining straps and projections being under the plane of the plates, the projections of one plate underlying an adjacent plate with a spacing in the manner of the spacing between the units; 15 and a plastic filler in the spaces between the plates.
2. A metal tile wall comprising a supporting wall backing; metal tile plates, each having a plurality of tile units spaced one from another, the plates being cut through be-

tween the units and having joining straps at intervals, said plates having securing projections along their edges, said joining straps and projections being under the plane of the plates, the projections of one plate underlying an adjacent plate with a spacing in the manner of the spacing between the units; 10 and a plastic filler in the spaces between the plates, said filler extending under the plates seating the plates and locking the cement. 75

3. A sheet metal tile plate having a plurality of spaced tile units with inturned flanges at their edges, the inner edges of the flanges of the units being connected by the metal of the plate, portions of the metal in the spaces between the tile units being cut away and spacing the inturned flanges of the tile units from a backing to which the tile may be attached. 80
